ALEXANDER C. TWINING, OF NEW HAVEN, CONNECTICUT.

Letters Patent No. 75,080, dated March 3, 1868.

IMPROVED SOCKET FOR CASTERS.

The Schedule referred to in these Letters Patent and making part of the same.

Be it known that I, ALEXANDER C. TWINING, of the city and county of New Haven, and State of Connecticut, have invented a new and useful Attachment of Sockets for Casters and the like; and I do hereby declare that the following is a full, clear, and exact description of the same, reference being had to the annexed drawing, of which—

Figure I, and the "section" beneath and in connection with it, show the attachment for a bed, as, for instance, the bed or plate of a caster; and

Figure II, and its corresponding "section," show the same for a socket.

In both figures *b b b* is the bed, socket, band, or the like. In Fig. I this has a number, say eight, of oblique parallel ridges, cast or made upon its exterior, and in Fig. II the like are shown on the interior. Some of these ridges are marked by *r r r r*, both on the main figures and the sections. The ridges *r r r r*, taper from their bases to a blunt edge, as seen most obviously in both the "sections." This edge is not necessarily a spiral, although such, in a slight degree, to the eye, when viewed in the drawing. It may be made spiral, if desired, but, otherwise, it may lie all in one plane, like the curved edge of a scimitar, as will be immediately apparent by looking along such edges of the actual casting. They must not, like screw-threads, run round and round, as the use and purpose, explained farther on will evidently show, but they should lie along, with only such moderate obliquity that the force to set the bed (as Fig. I) into the timber, or to set the timber into the socket, (as in the shape of Fig. II,) cannot be tangential or screwing, but must be applied lengthwise, as in driving a bolt or nail. The rotation consequent upon driving in the piece is an incident only, without importance otherwise to the improvement or effect. The collar *c c*, Fig. I, limits the depth of penetration, and also supplies a base of support to the superincumbent weight. Much more do the ridges, by their oblique set, supply a like base. To this the hold by friction also contributes, and it will require but ordinary attention in the mechanic to secure, yet farther, that the bed shall reach to and abut upon the end of the base.

For exemplification of the above, let Fig. I represent the bed or socket for the pintle of a caster. It is to be driven into a base suited in diameter to *b b b*. I am aware that screw-bolts have been proposed, for other uses, which are adapted to be driven. These, however, would split the small wooden stocks, the legs of a table, for example, into which mine can be driven. Again, the former can be taken out by unscrewing, whereas it is a distinct and important property that mine, even if feebly attached, cannot be screwed out, as by the action of a caster or otherwise. In fact, also, my article shows the two striking peculiarities that it does not, in the wood, hold lengthwise of its own stock or shank, as a screw, but it holds in a plane across the length, and tangentially around the circumference, and so against splitting. Secondly, it can be taken out, as well as set in, by a force lengthwise applied, while the friction and situation of its ridges prevent any screwing. One point of the construction by which this is realized, besides the acute triangular section of the ridges, is such a form and position as make their edges lie completely, or nearly, in planes acutely and equally inclined to the axis of the socket or stock. This formation encloses ribs of wood between the ridges, and thus holds the parts together.

For beds driven into a very small stock, it will be an additional preventive of splitting to run valleys, *v v*, at the base of the ridges *r r*, in which the compressed wood around the bore can partially spread. These depressions or "valleys" are most distinctly exhibited in the "section through S S" and the "section I I" in the accompanying drawing. It will also be evident, on a bare inspection of the "sections," that these valleys *v v* might be so numerous and set so closely as to form, of themselves, by the separating metal, substantially the rigid surface herein described.

Fig. II exhibits the same things on the interior surface of a socket or ring, thus illustrating one variation, or equivalent, of all the above. The ridges, however, are there seen not to traverse the entire cylindric length, but to alternate in one series and another of short ridges mutually overlapping. Of such series as many may be made as shall be desired. This form of ridge-bed admits the attachment of a wooden handle by simply driving in the latter. A pin, *p*, or pins, may be driven through the wood into an orifice in the metal. The same is obvious as applied to any other than these two forms of the invention.

Claim.

What I claim as my invention, and desire to secure by Letters Patent, is—

1. The socket or stock, made with ridges edged, or nearly so, in planes acutely and equally inclined to the axis of the socket, as and for the purpose described.
2. The valleys, along the ridge bases, for an increased prevention of splitting, as herein described.

ALEX'R C. TWINING.
